Primary Examiner — Ian Simmons*Assistant Examiner* — Yolanda Robinson(74) *Attorney, Agent, or Firm* — Lee & Hayes, P.C.(57) **CLAIM**

The ornamental design for a delivery truck box, as shown and described.

DESCRIPTION

FIG. 1 is a front perspective view of a delivery truck box; FIG. 2 is a front view thereof;

FIG. 3 is a back view thereof;

FIG. 4 is a left-side view thereof;

FIG. 5 is a right-side view thereof; and,

FIG. 6 is a top view thereof.

The broken lines depict portions of the delivery truck box that form no part of the claimed design.
